Primary Examiner — George D. Kirschbaum*Assistant Examiner* — Lillian Windham(74) *Attorney, Agent, or Firm* — Westbridge IP LLC(57) **CLAIM**

The ornamental design for a weather station, as shown and described.

DESCRIPTION

FIG. 1 is a front elevational view of a weather station showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front perspective view shown in a state of use; and,

FIG. 8 is a rear perspective view shown in a state of use. The broken line showing in FIG. 7 is included for the purpose of illustrating portions of the weather station and forms no part of the claimed design.
